Primary Examiner — Cynthia Ramirez*(74) Attorney, Agent, or Firm* — Brooks Kushman P.C.(57) **CLAIM**

The ornamental design for a road paving machine, as shown and described.

DESCRIPTION

FIG. 1 is a left side view of a road paving machine showing my new design;

FIG. 2 is a front view thereof;

FIG. 3 is a right side view thereof;

FIG. 4 is a rear view thereof;

FIG. 5 is a top view thereof;

FIG. 6 is a front, left, top perspective view thereof; and,

FIG. 7 is a rear, right, top perspective view thereof.
